UNITED STATES PATENT OFFICE

2,608,913

SUCTION BOX CONNECTION TO MANIFOLD

Samuel M. Bratton, Wilmington, Del., assignor to
The Pusey & Jones Corporation, Wilmington,
Del., a corporation of Delaware

Application October 15, 1946, Serial No. 703,454

17 Claims. (Cl. 92—51)

1

The present invention relates to paper making machinery and, more particularly, to suction boxes of Fourdrinier machines and their connections to suction and water discharge lines.

A primary object of the invention is to improve the connections between suction boxes, mounted upon the vertically adjustable or stationary supporting frames of Fourdrinier machines, and the suction and water discharge lines. Another vital object is to provide improved suction box connections for installations of this kind, which will facilitate reciprocation, rotary or other motion of the suction boxes in their normal operation, transversely or otherwise with respect to the length of the Fourdrinier wire, below its upper, operative run.

As is well-known to those skilled in the art, the frames or tables of most Fourdrinier machines, including the main supporting frames thereof, are mounted for vertical adjustment, to vary the angle of inclination of the run of the wire as a whole, from the head box to the couch roll. The suction boxes, mounted below the wire, extending across the machine and supported by the rails above the frames, must be raised and lowered when these adjustments are made. Also when the covers of the suction boxes wear or are re-conditioned, adjustment of the suction box in relation to the supporting rails is required. Hence, flexible connections must be provided from the fixed suction and water discharge lines to the suction boxes, to accommodate the adjusting movement, as well as the normal movements of the boxes relative to the wire, employed to prevent the wire from wearing grooves in the upper surfaces of the boxes.

In the past, large rubber conduits, reinforced exteriorly and interiorly with coils of wire, to prevent their collapse, have been inserted in the lines between the suction boxes and the fixed manifolds, usually in angularly disposed, vertical and horizontal sections, to provide the desired flexibility.

The constructions, however, have been large, space consuming, cumbersome, unwieldy, and of insufficient flexibility. Moreover, great difficulty and loss of time have been encountered in replacing or re-conditioning worn sections.

In accordance with the present invention, these large, heavy, clumsy and expensive flexible sections are entirely eliminated, and an adjustable suction box connection is provided, which greatly facilitates a change in the vertically adjusted position of the Fourdrinier machine, and which accommodates the normal movement of the suc-

2

tion box in an improved manner. Also, the new connecting structure facilitates the removal and replacement of a worn suction box.

A further object of the invention is to provide, in combination with a vertically adjustable Fourdrinier machine having suction boxes carried by the supporting rail thereof, a fixed manifold connected to fixed suction and discharge lines, and a vertically adjustable connection, including a vertically slideable joint, between a coupling conduit section carried by the main supporting frame and the fixed manifold.

A further object of the invention is to provide a novel connection between a coupling conduit section carried by the main frame of a Fourdrinier machine and the suction box itself, whereby the suction box may be reciprocated and the coupling conduit section may remain relatively stationary.

A further object of the invention is to provide a novel seal between a fixed manifold and an adjustable coupling section carried by the main frame of a paper making machine.

Another object is to provide an improved seal between the upper end of such a coupling conduit section and a removable suction box, at either end thereof, at both ends, or at a point between the ends, adapted to permit normal reciprocations or other movements of the box and to facilitate removal of one box and the substitution of another.

Other and further objects and advantages of the invention will be apparent to those skilled in the art from a consideration of the specific embodiment of the invention shown in the accompanying drawings and described below.

In the drawings:

Figure 1 is a side elevation of the manifold connection and associated parts in accordance with the present invention.

Figure 2 is a central vertical section through the right hand portion of Figure 1.

Figure 3 is a horizontal section, showing the joint between the fixed manifold and the vertically adjustable conduit section.

Figure 4 is a top plan view.

Figure 5 is an end elevation, taken from the right of Figure 1, with certain parts removed.

Figure 6 is a vertical section taken on line 6—6 of Figure 4, and

Figure 7 is a vertical section on line 7—7 of Figure 2, on an enlarged scale.

In Figure 1, the main supporting frames of a Fourdrinier machine are indicated at 10 and 11. The frames are mounted for vertical adjustment,

as explained above, by any conventional means, such as the jacks 10' and 11', shown diagrammatically in Figure 1. A suction box 12, having a perforated cover 13 is carried by a pair of suction box supporting rails 15 at opposite sides of the machine, supported in turn by the main frames 10 and 11, in fixed relation with respect thereto, by conventional means, not shown. An angular bracket 16 is supported by each rail 15 for vertical adjustment with respect thereto by means of a screw 16', and may be locked in adjusted position by a bolt 16''. Each bracket 16 has a horizontal flange 17, overlying an extension 18 of the suction box and underlying the marginal portion of a plate 19 secured to the suction box extension. Hence, a slidible connection is provided between the flange 17 and the parts fixed with respect to the suction box, and the entire assembly may be raised and lowered by adjusting the screws 16', for instance, to accommodate suction box covers of different thicknesses.

As is well understood in the art, a movable bridge 14, having rollers 14' associated therewith may be used to carry the end of the suction box when one is being installed or removed from the machine. The bridge or carriage 14 is movable from one box to another, in accordance with conventional practice.

At its terminal portion 20, the suction box extension 18 is shaped to provide a vertical way 21 in which a sliding block 22 is mounted for vertical reciprocations, under the influence of a roller 23 mounted on the eccentric portion 24 of a rotatable shaft, having a center at 25. Hence, as the shaft rotates, the suction box extension and the box as a whole are reciprocated longitudinally, transversely of the length of the wire, supported above the perforated cover 13 of the box; or any other motion applied to either or both ends of the suction box may be employed.

A hand wheel 26, connected to a threaded shaft 27 may be provided for shifting marginal baffle plates associated with the suction box cover, to block off marginal portions thereof, and to accommodate paper webs of different widths, as is well understood in the art.

In the past, suction boxes have been connected to sources of suction and water discharge lines by large, heavy flexible conduit sections. In accordance with the present invention, however, an improved connecting system is provided.

For each suction box associated with the Fourdrinier machine, there is provided a hollow manifold casting 30, supported upon the floor 31 and having upper and lower connections 32, 33, leading to suction and discharge lines 34, 35, respectively. Each manifold member is provided with a vertically elongated opening 36, intermediate its upper and lower ends. The margins surrounding the opening 36 are grooved as at 37, for the reception of a continuous sealing means, which may comprise a pair of grooved strips of rubber, molded graphite composition, or the like 38, 39, and an intermediate, continuous, compressible rubber tube 40. A removable plate 41 above the opening 36 may be employed to assist in retaining the sealing devices in place.

The supporting frame 10 of the Fourdrinier machine carries a coupling conduit section 45, 70 having angularly disposed flanges 46, 47 bolted or otherwise secured to the frames. The coupling section 45 terminates at its lower end in a lateral opening 49 of less height than the opening 36 in the manifold and registering with a

portion thereof. Upwardly and downwardly extending flanges 50, 51, constituting continuations of the upper and lower margins of the opening 49, are disposed in sealing contact with the outer face of the sealing ring 39. In the lowest adjusted position of the frame 10, as shown in Figure 2, the flange 50 blocks and closes the portion of the vertically elongated opening 36 above the conduit opening 49 of the coupling section. It will be apparent that, when the main supporting frame 10 is raised, the position of registry of openings 49 and 36 will be correspondingly changed, and the flange 51 will close a portion of the opening 36. In other words, the coupling section 45 is vertically slidable relative to the fixed manifold, but sealing contact is always maintained between the face thereof and the sealing strip surrounding the opening in the manifold.

At its upper end, the coupling section 45 carries an apertured plate 55, to which is attached a tubular bellows of thin flexible metal or other material, well-known in the art. The upper end of the compressible and extensible section so provided is hermetically sealed to an apertured coupling plate 57, carrying downwardly extending bolts 58, extending loosely through the lower plate 55 and the flange 45' of the coupling section 45. Coil compression springs 59 surround the bolts and urge the plate 57 upwardly, the upward movement of the plate being limited, when the suction box extension is removed, by bolt heads 60, spaced below the supporting flange 45'.

The upper plate 57 is provided with a raised, annular ring 63, holding in place a sealing ring 64, adapted to make sealing contact with the lower face 65 of the suction box extension surrounding the opening 66 therein.

The upper coupling plate 57 is also provided with a pair of marginal, raised cam tracks 68, having inclined end surfaces 69, 70, adapted to cooperate with cam projections 71 associated with the suction box extension, to cause the upper coupling plate 57 to be depressed when the suction box and its extension are moved a substantial distance transversely of the machine. For instance, if the suction box is moved manually a predetermined distance to the left, from the position shown in Figure 1 for purposes of removing the box, the lower surface of the cam extension 71 will engage the inclined portion 70 of the cam track 68 and depress the same, moving the sealing ring 64 out of contact with the margins of the opening 66 in the suction box extension and permitting ready withdrawal of the suction box. Similarly, when a new or replacement suction box is inserted, by manual movement from left to right, supported by rollers 14' on carriage 14, the cam extension 71 will ride up upon the inclined end 69 of the cam track 68, thereby depressing the latter, until the margins of the opening 66 in the suction box extension are in proper registry with the sealing ring, whereupon the upper plate 57 will snap upwardly into place, under the influence of the springs 59.

The normal reciprocations or other movements of the suction box, effected by the above described eccentric 24, or other mechanisms, are relatively short in length, the main purpose thereof being to prevent the Fourdrinier wire from wearing grooves in the upper surface of the box. These reciprocations or movements are permitted by a sliding movement between the lower face of the suction box extension and the upper

surface of the sealing ring 64. It will be noted that there is sufficient space between the lower left-hand surface of the cam projections 71, carried by the suction box extension and the inclined end surfaces of the cam tracks 68 so that the reciprocation of the suction box may occur, without bringing the cam surfaces into camming relation. However, when the suction box and its extension are moved a greater distance, as for a box changing operation, the cam surfaces come into engagement, to depress the coupling plate as previously described.

Thus, the suction conduit system of the present invention includes a vertically slidable adjustable seal, between the fixed manifold and the coupling section carried by the Fourdrinier supporting frame, permitting vertical adjustment of the entire machine relative to the manifold and the fixed suction and water discharge lines; and, in addition, a horizontal seal making a slideable connection between the suction box extension and the coupling conduit, permitting normal reciprocation or other movements of the box in use. These slideable connections take the place of, and entirely eliminate, the heavy, clumsy, space consuming reinforced rubber pipe sections heretofore used.

It should be understood that the invention is not limited to the specific details of construction shown in the accompanying drawings and described above, but covers all modifications coming within the scope of the appended claims and their equivalents.

I claim:

1. In a Fourdrinier machine having a suction box supported by the vertically adjustable supporting rails thereof and having fixed suction and water discharge lines, means establishing communication between the suction box and said lines, comprising a fixed manifold member connected to said lines, a coupling conduit member connected to said box and including a rigid section carried by said rails, one of said members having surfaces defining a vertically elongated laterally facing opening, the other member having a vertically elongated sealing surface registering with the margins of and being of greater height than said opening and said sealing surface having an opening therein of less height than, and registering with a portion of the elongated opening, said members being relatively vertically adjustable to change the elevation of registry of said openings, said sealing surface sealing the margins of the elongated opening in all adjusted positions of the members.

2. In a Fourdrinier machine having a suction box supported by the vertically adjustable supporting rails thereof and having fixed suction and water discharge lines, means establishing connection between the suction box and said lines, comprising a fixed manifold connected to said lines and having surfaces defining a laterally facing opening, and a coupling conduit member connected to the suction box and including a rigid section having a vertically elongated sealing surface registering with said opening in the manifold throughout the entire range of vertical adjustments of the rail and suction box.

3. In a Fourdrinier machine having a suction box mounted for movement with the main vertically adjustable supporting frame thereof and having fixed suction and water discharge lines, means establishing connection between the suction box and said lines, comprising a fixed manifold connected to said lines and having surfaces

defining a laterally facing opening, and a coupling conduit member connected to the suction box and including a rigid section having a vertically elongated sealing surface registering with said opening in the manifold throughout the entire range of vertical adjustments of the rail and suction box, said laterally facing manifold opening being vertically elongated and having its margins sealed by said vertically elongated sealing surface in all adjusted positions of the latter.

4. In a Fourdrinier machine having a suction box mounted for reciprocating movements in the direction of its length, transverse to the wire, and carried by vertically adjustable supporting rails, and fixed suction and water discharge lines; means establishing connection between the suction box and said lines, said means comprising a fixed manifold connected at its upper and lower ends to said lines and having surfaces defining a vertically elongated opening in its side wall, conduit means connected to the suction box at one end and terminating at the other end in a rigid member having a laterally facing opening and a vertically elongated sealing surface projecting from the margins thereof and making sealing contact with the margins of the manifold opening, said conduit means including a section movable with the suction box and another section fixed with respect to the supporting rails.

5. In a Fourdrinier machine of the type having a horizontally reciprocating suction box mounted for vertical movement with the main vertically adjustable frame thereof, and fixed suction and water discharge lines; means establishing connection between the suction box and said lines, comprising a fixed manifold member connected to said lines and having surfaces defining a laterally facing opening, a coupling member fixedly carried by said frame and including a rigid section, a sealing connection between said members, comprising an opening in the coupling member registering with said laterally facing opening, one of said members having a sealing surface making vertical sliding sealing contact with the margins of the opening in the other member, and a horizontally slideable connection between the coupling member and the suction box, maintaining a seal therebetween during reciprocating movements of the latter.

6. In a paper making machine having a suction box mounted for vertical adjustment with the vertically adjustable main frame of the machine, and fixed suction and water discharge lines, means for establishing connection between the box and said lines, comprising a fixed manifold connected to said lines and having surfaces defining a vertically elongated opening leading to its interior, conduit means connected at one end to the suction box and having at the other end thereof a rigid section provided with an opening of smaller vertical dimension than said manifold opening and a flange extending vertically from the margins of the last mentioned opening and covering the portion of the manifold opening cut of registry with the conduit opening, and sealing means between the margins of the manifold opening and said flange.

7. In a paper making machine having a suction box mounted for vertical adjustment with the vertically adjustable main frame of the machine, and fixed suction and water discharge lines, means for establishing connection between the box and said lines, comprising a fixed manifold connected to said lines and having surfaces defining a vertically elongated laterally facing

opening leading to its interior, conduit means connected at one end to the suction box and having at the other end thereof, a rigid section slidably connected to the manifold for vertical adjustment with respect thereto, said conduit means at the latter end having surfaces defining an opening of less vertical dimension than the manifold opening and registering with different portions thereof at different vertically adjusted positions, and a flange projecting upwardly and downwardly from the upper and lower margins of the second mentioned opening and making sealing contact with the margins of the manifold opening in all vertical adjustments of the conduit means.

8. In a paper making machine having a suction box mounted for vertical adjustment with the vertically adjustable main frame of the machine, and fixed suction and water discharge lines, means for establishing connection between the box and said lines, comprising a fixed manifold connected to said lines and having surfaces defining a vertically elongated opening leading to its interior, conduit means connected at one end to the suction box and having at the other end thereof, a rigid section slidably connected to the manifold for vertical adjustment with respect thereto, said conduit means at the latter end having surfaces defining an opening of less vertical dimension than the manifold opening and registering with different portions thereof at different vertically adjusted positions, and a substantially plane faced flange projecting from the margins of the second mentioned opening and making sealing contact with the margins of the manifold opening in all vertical adjustments of the conduit means.

9. In a paper making machine having a suction box mounted for vertical adjustment with the vertically adjustable main frame of the machine, and fixed suction and water discharge lines, means for establishing connection between the box and said lines, comprising a fixed manifold connected to said lines and having surfaces defining a vertically elongated opening leading to its interior, a suction box extension having a downwardly facing opening, a coupling conduit section having its upper end operatively connected to the extension opening and its other end terminating in a vertically elongated, rigid flange disposed in registry with the margins of the manifold opening said flange having surfaces defining an opening therethrough of less height than the latter, and sealing means between the margins of the manifold opening and said flange, whereby the coupling conduit may make connection with the manifold at a plurality of different vertically adjusted positions.

10. In a paper making machine having a suction box and suction and water discharge lines, means for establishing connection between the box and said lines, comprising a fixed manifold connected to said lines, a suction box extension having a downwardly facing opening, means for longitudinally reciprocating the extension and the suction box, a coupling conduit below the extension having an upwardly facing opening, a flexible conduit section interposed between the coupling conduit and the suction box extension, and means for connecting the coupling conduit to the manifold.

11. In a paper making machine having a vertically adjustable suction box and fixed suction and water discharge lines, means for establishing connection between the box and said lines, com-

prising a fixed manifold connected to said lines, a suction box extension having a downwardly facing opening, means for longitudinally reciprocating the extension and the suction box, a coupling conduit below the extension having an upwardly facing opening, a flexible conduit section interposed between the coupling conduit and the suction box extension, said coupling conduit having a lateral opening and a vertically elongated flange adjacent thereto, positioned in registry with the margins of the manifold opening, and sealing means between said flange and said margins, permitting vertical adjustment of the suction box and extension, and the coupling conduit with respect to the manifold.

12. The combination with a reciprocating suction box carried by a vertically adjustable supporting rail in a paper making machine having associated therewith, fixed suction and water discharge lines; of means for establishing communication between the suction box and said lines irrespective of the vertically adjusted position of the box and rail, said means comprising a fixed manifold connected to the lines at its upper and lower ends and having a vertically elongated intermediate opening, a coupling conduit section supported for vertical adjustment with said rail, having an opening of reduced height communicating with the manifold opening and flange means above and below its opening covering the portion of the manifold opening out of registry therewith, an extension on said suction box having a downwardly facing opening in its bottom, and an extensible upwardly pressed conduit at the upper end of the coupling section having its upper end slidably engaging the suction box extension around the opening therein, permitting longitudinal reciprocating movements of the suction box relative to the rail-carried coupling section.

13. In a paper making machine, a suction box supported in vertically fixed relation to the main supporting frame of the machine, a coupling conduit carried by said frame and having a compressible and extensible section at its upper end, spring means urging the latter upwardly, sealing means at the upper end of the flexible section, a suction box extension having a downwardly facing opening having margins registering with the sealing means, and inter-engaging cam means associated with the suction box extension and the flexible section, to compress the latter against the force of the spring means and to relieve pressure on the sealing means when the suction box is moved translationally for the removal or replacement of the suction box.

14. In a Fourdrinier machine having a main frame and suction box supporting rails fixed with respect thereto, a suction box carried by the rails for limited reciprocating movement, a coupling conduit section carried by the frame below the suction box and having a flexible section at its upper end, a sealing ring carried by the upper end of the flexible section, a suction box extension having an opening defined by sealing surfaces engaging the sealing ring, and means for moving the said surfaces away from said ring upon relative translational movement between the suction box extension and the flexible section, for suction box removal or replacement, said means comprising cam surfaces carried by the suction box extension and the flexible section respectively.

15. In a Fourdrinier machine having a main frame and suction box supporting rails fixed with

respect thereto, and suction boxes adapted to be installed and removed by relative translational movement with respect to said rails, a suction connection for each suction box, comprising a suction conduit fixed with respect to the frame and rails having a flexible upper end terminating in an apertured coupling plate, resilient means urging the plate upwardly, a sealing ring mounted on said plate surrounding the opening therein, cam means on said plate, and additional cam means fixed with respect to the suction box and positioned to ride upon the first mentioned cam means, to depress said plate and to move the sealing ring out of contact with the suction box upon relative translational movement of the box with respect to the conduit.

16. In a Fourdrinier machine having a main frame and suction box supporting rails fixed with respect thereto, and suction boxes adapted to be installed and removed by relative translational movement with respect to the rails, a suction connection for each suction box, comprising a suction conduit fixed with respect to one of the frames and rails, having a flexible upper end terminating in an apertured coupling plate, resilient means urging the plate upwardly, a sealing ring mounted on said plate surrounding the opening therein, a pair of cam tracks having inclined end faces positioned on said plate, and additional cam means fixed with respect to the suction box and positioned to ride upon said cam tracks, to depress said plate and to move the sealing ring out of contact with the suction box upon relative translational movement of the box with respect to the conduit.

17. In a Fourdrinier machine having a main frame and suction box supporting rails fixed with respect thereto, and suction boxes adapted to be installed and removed by relative translational

movement with respect to the rails, and adapted for limited reciprocating movement, means for reciprocating each suction box and means for connecting the same to a source of suction, the last mentioned means comprising a suction box extension having a downwardly facing opening therein, a coupling conduit fixedly carried by said frame and terminating at its upper end in a flexible section and an apertured coupling plate, a sealing ring carried by said plate and slidably engaging the suction box extension around the opening therein, whereby the suction box and said extension may reciprocate relative to the coupling plate and ring, and cam means fixed with respect to the suction box extension and the coupling plate, respectively, for lowering the plate and the sealing ring upon said translational movement of the suction box and its extension.
